UNITED STATES PATENT OFFICE.

THEODORE C. STEIMER, DECEASED, LATE OF PITTSBURGH, PENNSYLVANIA; BY CHARLES M. STEIMER, EXECUTOR, OF ZANESVILLE, OHIO, ASSIGNEE, BY MESNE ASSIGNMENTS, TO THE HARTFORD SPECIAL MACHINERY COMPANY, A CORPORATION OF CONNECTICUT.

GLASS-WORKING APPARATUS.

Original application filed February 12, 1910, Serial No. 543,582, and in Canada January 28, 1918.
Divided and this application filed October 27, 1925. Serial No. 65,190.

The invention herein claimed relates to mechanism for fabricating pressed or blown articles from charges of molten glass, and is illustrated as applied to a press for making table ware and the like.

The object is to improve the operation of glassware fabricating machines, more especially by providing improved driving mechanism for turning a mold table step-by-step to bring the molds carried by the table into successive working positions.

In the accompanying drawing, which is a reproduction of the sixth sheet of the drawings of the above-identified original application,

Figure 1 is a vertical section taken through the center of a glassware pressing machine also showing some of the molds in elevation, the section being on the line (7) in Fig. 2; Fig. 2 is a section taken on the line (8) of Fig. 1, showing especially the operation of the press plunger;

Fig. 3 is a horizontal section on the line (9) in Fig. 1;

Fig. 4 is a detail showing in side elevation the shifting plungers in another position; and

Figs. 5 and 6 are details, respectively in vertical section and side elevation, of certain parts of the driving mechanism for the table of the press.

A main power shaft 68 is mounted in bearings 69 of the press frame 70 and carries a gear meshing with another gear 72 on a shaft 73 mounted in bearings 73* on the pivoted frame 74. This shaft 73 carries a cam 75 for engaging the cross-head 76 of the main press plunger 77, and the cross-head 76 is connected to or made integral with another cross-head 78 which is engaged by two cams 79 also keyed on shaft 73 and arranged to lift the plunger 77. The plunger and cross-heads are preferably counter-weighted by weights W mounted on the frame 80 which rests upon the same base 70* as the press frame 70 carrying the shaft 68. This frame 80 stands between the two side wings of the pivoted frame 74, as will appear from Fig. 2 and while the frame 80 is stationary, just like the standard 70, the frame 74 is pivoted at 68 and its lower or tail portion 74* rests against the stationary

standard 70. If there is induced any excess pressure on the plunger 77, it will be seen that the plunger and its operating cams and shaft again all rise by lifting the frame 74 and rotating it around 68 as a center. It is held down however, by its own weight and by the additional provision of a lever 81 whose pivot 82 rests in bearings 83 on frame 70 and which has a hooked end engaging the tail of frame 74 to hold it against the standard 70. The lever 81 is graduated and has a sliding weight 84 by which to accurately regulate the limiting pressure of the plunger. This enables me to avoid excess pressure and treat all the articles alike in the presses, the plunger giving way even if there should be too much glass in the mold instead of crushing or crizzling the glass.

The main plunger 77 carries integral with it a frame 85 which reciprocates in guides 86 and has pivoted to its bottom, (as shown more clearly in Fig. 4), a supplementary oscillating frame 87 which carries two supplementary plungers 88 fixed on the rim 87*. These supplementary plungers are alternately brought in position over the molds M by the engagement of a pair of integral arms 89 on frame 87, with cams 90 fixed on the bottom of the revolving table 91 of the press.

This table 91 carries any convenient number of molds M, and it is moved in a step by step motion, on the bearing plate 92 by means of a conical gear 93 fixed inside it and engaging a bevel gear 94 on the shaft 95. This shaft 95 is operated intermittently by a pinion 96 engaging a vertically reciprocating rack 97 operated by a link 98 attached to a wrist pin 99 on two discs 100 fixed on the shaft 68. It will be understood that by the constant rotation of these discs on shaft 68 the rack 97 is continuously reciprocated, and in order that the press table may be driven by shaft 95 always in the same direction, I provide on the shaft 95 a keyed disc 101 which carries a spring-pressed retreating bolt 102 engaging an inclined slot 103 in the side of the pinion 96; this pinion 96 riding freely on shaft 95 in one direction, but being engaged by bolt 102 in the opposite direction and thereby intermittently revolving the shaft 95.

It will be understood that the mold table

brings the molds M successively under the position of the main plunger 77, and by this revolving motion alternately shifts into alignment the two supplementary plungers 88, which are thus driven into the mold in the usual way; but it is to be noted that by this means I have always a cold plunger to press the glass and this very much increases the speed of the machine without danger of sticking or overheating. From the position under the plunger, the glass in the molds is cooling until it reaches the position O, X as shown in Figs. 1 and 3, when the tumbler T is ejected by the rising of a valve 104 whose stem has a roller 105 at this time engaged with a cam track 106, fixed to the bed-plate 92 of the machine.

In the operation of the machine, each mold receives its charge of glass at a receiving position and thence it passes by reason of the revolution of table 91 in a step-by-step movement until the mold comes under one of the subsidiary plungers 88. The plunger is then depressed by cam 75, the pivoted frame 74 relieving the pressure at the proper point, and then the plunger being raised by cams 79. The subsidiary plungers 88 are alternated in successive molds. The stopping of the mold under the plunger is accomplished by the interruption of the travel by return of pinion 96 in its idle position as it is driven by rack 97. As the tumbler comes to the take-out position, it is ejected from the mold M by the stem of the valve traveling up the track 106.

Variations may be made in the construction and arrangement of parts, within the scope of the appended claims.

I claim as my invention:

40 1. A machine for fabricating glassware comprising a rotatable mold table, a gear carried by said mold table, a driving gear rotatable on an axis displaced from the axis of said mold table and meshing with said first-named gear, and a reciprocable rack connected to rotate said driving gear intermittently in one direction.

50 2. A machine for fabricating glassware comprising a rotatable mold table, a gear secured to said mold table and movable concentrically therewith, a driving gear meshing with said first-named gear, a shaft displaced from the axis of said mold table and carrying said driving gear, a pinion mounted upon said shaft, and a reciprocable rack adapted to impart intermittent rotation to said shaft through said pinion.

60 3. A machine for fabricating glassware comprising a rotatable mold table, a gear carried by said mold table and movable concentrically therewith, a driving gear meshing with said first-named gear, an oscillable toothed clutch member arranged to swing upon the axis of said driving gear, a reciprocable rack bar meshing with said toothed

clutch member, means for reciprocating said rack bar, and means for intermittently coupling and uncoupling said clutch member and said driving gear so as to impart step-by-step rotation to said mold table 70 when said rack rocks said toothed clutch member in one direction and for permitting said rack to rock said clutch member in the opposite direction without moving said mold table. 75

4. A machine for fabricating glassware comprising a rotatable mold table, a gear carried by said mold table and movable concentrically therewith, a driving gear meshing with said first-named gear, an oscillable toothed clutch member arranged to swing upon the axis of said driving gear, a reciprocable rack bar meshing with said toothed clutch member, means for reciprocating said rack bar, and means for intermittently coupling and uncoupling said toothed clutch member and said driving gear so as to impart step-by-step rotation to said mold table, the said coupling and uncoupling means comprising a clutch member associated with said driving gear and rotatable therewith, and a spring-pressed pin arranged to cause said clutch members to move together in one direction while permitting said toothed clutch member to move in the opposite direction without moving the other clutch member. 80 85 90 95

5. A glass shaping machine comprising a movable support, a plurality of molds carried thereby, a main pressing plunger associated with said molds, a member pivotally mounted on said plunger for oscillatory movement about a horizontal axis, a plurality of subsidiary plungers carried by said member, and mechanism for oscillating said member to alternately position said subsidiary plungers in axial alignment with said main plunger. 100 105

6. A glass shaping machine comprising an intermittently rotatable table, a series of molds carried thereby, a main pressing plunger, a support carried by said main plunger, a plurality of subsidiary plungers mounted on said support for oscillatory movement about a horizontal axis, and means actuated by the rotation of said table for swinging said subsidiary plungers alternately in axial alignment with said main plunger. 110 115

7. A glass shaping machine comprising an intermittently rotatable table, a series of molds carried thereby, a main pressing plunger, a support mounted on said main plunger for oscillatory movement about a horizontal axis, a plurality of subsidiary plungers carried by said support, a plurality of cam surfaces carried by said table and adapted to swing said support to alternately position said subsidiary plungers in axial alignment with said main plunger. 120 125 130

8. A glass shaping machine comprising a mold, a pressing plunger associated therewith, a support mounted adjacent to said plunger, an arm pivotally mounted on said support, means carried by said arm for actuating said plunger, and a latch mechanism for maintaining said arm and said plunger actuating means in operative position during the normal operation of said machine and adapted to yield in the event that said plunger encounters excess resistance during the pressing operation.

9. A glass shaping machine comprising a mold, a pressing plunger associated therewith, a support mounted adjacent to said plunger, an arm pivotally mounted on said support, means carried by said arm for actuating said plunger, and a safety device for maintaining said arm and said plunger actuating means in operative position during the normal operation of said machine, and adapted to yield at a predetermined pressure.

10. A glass shaping machine comprising a mold, a pressing plunger associated therewith, a support mounted adjacent to said plunger, an arm pivotally mounted on said support, means carried by said arm for actuating said plunger, and a safety device for maintaining said arm and said plunger actuating means in operative position during the normal operation of said machine and adapted to yield in the event that said plunger encounters excess glass in said mold, and means for varying the degree of pressure exerted by said plunger.

11. A glass shaping machine comprising a mold, a pressing plunger associated therewith, a support mounted adjacent to said plunger, an arm pivotally mounted on said support, means carried by said arm for actuating said plunger, and a safety device for maintaining said arm and said plunger actuating means in operative position during the normal operation of said machine and adapted to yield in the event that said plunger encounters excess glass in said mold, and means for adjustably determining the pressure required to cause said safety device to yield.

12. A glass shaping machine comprising a mold, a pressing plunger associated there-

with, a support mounted adjacent to said plunger, a shaft journaled in said support, an arm pivotally mounted on said shaft, a second shaft journaled in said arm, means carried by said second shaft for actuating said plunger, and means for permitting said arm and said plunger actuating means to swing on said first-mentioned shaft to relieve pressure on said plunger in the event of excess glass in said mold.

13. A glass shaping machine comprising a mold, a pressing plunger associated therewith, a support mounted adjacent to said plunger, a shaft journaled in said support, an arm pivotally mounted on said shaft, a second shaft journaled in said arm, means carried by said second-mentioned shaft for actuating said pressing plunger, and latch mechanism for releasably maintaining said arm and said actuating means in operative position during the normal operation of said machine and adapted to yield to relieve the pressure exerted on said plunger by said actuating means when a predetermined pressure is reached.

14. A glass shaping machine comprising a mold, a pressing plunger associated therewith, a support mounted adjacent to said plunger, a shaft journaled in said support, an arm pivotally mounted on said shaft, a second shaft journaled in said arm, means carried by said second-mentioned shaft for actuating said pressing plunger, means for driving said first-mentioned shaft, intermeshing gears fixed to each of said shafts for operating said actuating means, and means for releasably maintaining said arm and said plunger actuating means in operative position during the normal operation of the machine.

15. A glass shaping machine comprising a mold, a pressing plunger associated therewith, a support mounted adjacent to said plunger, an arm pivotally mounted on said support, means carried by said arm for actuating said pressing plunger, and means adapted to permit said arm to move relative to said plunger to relieve pressure exerted thereon by said actuating means when a predetermined pressure is reached.
